ADSORBER AND SYSTEM

Ernest Baldwin Miller, Baltimore, Md., assignor,
by mesne assignments, to The Davison Chemical Corporation, Baltimore, Md., a corporation of Maryland

Application February 16, 1932, Serial No. 593,398

17 Claims.

(Cl. 183—49)

This invention relates to adsorption systems and apparatus therefor.

It is a general object of the present invention to provide novel and improved adsorption systems and adsorber apparatus.

More particularly, it is an object of the invention to provide an adsorber of the continuous or rotary type wherein there is a minimum heat loss, resulting in maximum efficiency, brought about by maintaining portions of the gases being treated and portions of the activating gases which are at different temperatures out of contact with the opposite sides of baffles, partitions and the like so that there is no heat transfer between portions of the same gas at different temperatures.

An important feature of the invention resides in the novel construction of the adsorber unit wherein an adsorption chamber is formed between two figures of revolution, preferably cylinders, divided into a plurality of compartments by partitions, each compartment having, interposed between the ends thereof, a bed of adsorbent material which must be traversed by gases flowing from one end of the compartment to the other end in which the exposed surface of each adsorber bed has an area many times greater than the cross section of the compartment normal to the direction of flow of the gases, whereby great adsorption capacity is provided in a minimum volume and the resistance to gas flow is maintained at a minimum.

Another important feature of the invention resides in the arrangement of the adsorber beds on opposite sides of each partition plate in such a manner that the gases on the two sides of any partition plate, between adsorber beds undergoing the same operation, are at the same temperature, whereby no heat losses are effected through the partitions.

Still another important feature of the invention resides in the novel construction of the adsorber rotor wherein units comprising a partition and two screens form the connecting elements between inner and outer shells and define adsorber beds of uniform thickness between adjacent screens of adjacent units.

A further important feature of the invention resides in the means for maintaining gas-tight joints between stationary and movable parts of the adsorber and between those sections of the adsorber apparatus in which flow gases of different conditions, temperatures and constituents and particularly in the construction of the seals

which connect stationary and movable parts of gas passages.

Other and further features and objects of the invention will be more apparent to those skilled in the art upon a consideration of the accompanying drawings and following specifications, wherein is disclosed a single exemplary embodiment of the invention, with the understanding, however, that such modifications, variations and changes may be made therein as fall within the scope of the appended claims without departing from the spirit of the invention.

In said drawings:

Figure 1 is a schematic and diagrammatic showing of an adsorption system in accordance with the present invention and including a novel continuous rotary type adsorber;

Figure 2 is a fragmentary, arcuate section through the adsorber taken, for instance, on line 2—2 of Fig. 3;

Figure 3 is a plan view of the adsorber;

Figure 4 is a fragmentary section of the rotor taken at right angles to the axis of rotation and on line 4—4 of Fig. 2;

Figure 5 is a fragmentary, radial section taken on broken line 5—5 of Fig. 2;

Figure 6 is a perspective view of one of the partition and screen units forming the adsorbent beds, the upper portion being broken away on line 6—6 of Fig. 2;

Figure 7 is a side elevation of the whole adsorber unit; and

Figure 8 is a fragmentary, diagrammatic, horizontal, sectional view showing a modification.

Systems for the adsorption of condensable constituents of gases or the like, and particularly those for the dehydration of air should, as far as possible, be devoid of valves, dampers, control mechanisms and the like and this, as well as other important results, are achieved by systems and apparatus according to the present invention wherein a so-called continuous type adsorber is provided. The effect is obtained by providing a rotor containing a plurality of adsorber beds which are successively brought into the path of the gas to be treated and each then into the path of activating gases for revivifying the adsorbent material.

Heretofore, continuous rotary type adsorbers have been proposed, but due to their structural characteristics, placed decided limitations on capacity, as well as imparted undesired resistance to flow of the gases therethrough. This invention provides a plurality of adsorber beds, each very thin and of wide extent, all within a com-

pact space, so that gas at high velocities and in large quantities can be passed through an adsorber of relatively small cubical content. In this manner the size of the apparatus is very 5 materially reduced over that of previous rotary type adsorbers of the same capacity and over the stationary bed type adsorbers where several are used successively with adsorption and activating phase shifts by valve mechanism.

10 Referring now to the drawings for a better understanding of the invention, and first to Figure 1, wherein is disclosed schematically a system involving the present invention and adsorber apparatus. Here is shown by way of example, a 15 system for treating atmospheric air to reduce the absolute humidity thereof. Atmospheric air to be treated is taken in through the pipe 10 to the inlet of a fan or other air circulating means 11 and delivered under slight pressure into the pipe 20 12 and branch 13 for delivery into the sector 14, of the rotatable adsorption chamber 15, contained between the concentric inner and outer shells 16 and 17. The sector is defined by the 25 seals 18 and 19 on a stationary top hood and the corresponding seals 20 and 21 on a stationary bottom hood.

The air in passing through the adsorbent material contained in this sector is deprived of part of its moisture and is discharged into the inter- 30 cooler 23 where at least a portion of the heat of adsorption is removed in any suitable manner, as indirectly by cold water, and the partially dried and cooled air is delivered into the pipe 24 and to the sector 25 of the adsorber chamber defined 35 at the top by the seals 19 and 26 and at the bottom by the seals 21 and 27.

On this second pass through the adsorbent chamber, substantially all of the remaining moisture is removed from the air and it is discharged 40 into the aftercooler 29 where the heat of adsorption of the second pass is removed and the air is delivered to the pipe 30 for further use, for instance, for conditioning the atmosphere in houses or other buildings.

45 As previously stated, the adsorption chamber is continuously rotatable successively to bring small compartments containing adsorbent beds into the various sectors between the seals. Those adsorbent beds in the small chambers leaving the 50 sector for the second pass of the air are brought into the sector 31 defined at the top by the seals 32 and 26 and at the bottom by the seals 33 and 27. Through this sector hot gases are passed from the pipe 34 to heat the adsorbent material 55 and drive off the adsorbed moisture, the partially cooled gases and their burden of moisture being discharged through the pipe 35 to any suitable stack or the like.

The hot gases for this activating or revivifying 60 of the adsorbent material are produced by the combustion of any suitable fuel in the furnace 37. It is preferred, however, to burn a gaseous or liquid fuel which can be brought into the furnace through the pipe 38. The products of combustion 65 are withdrawn from the furnace through the pipe 39 by means of the blower 40 for delivery to the pipe 34 under low pressure.

Air for supporting combustion of the fuel is brought to the furnace through the pipes 41 and 70 41' and part of this air is preheated as the result of the operation of purging the adsorbent beds as they leave the activating phase and come into the sector between the seals 18 and 32 at the top and 20 and 33 at the bottom. These adsorbent 75 beds are hot and filled with burned gases from

the furnace and in order to remove these gases and partially cool the adsorbent beds before they move into position for use again in the first stage adsorption, air is blown through them. This may be readily effected by tapping off a pipe 42 5 from the air pipe 12 and leading it to this sector 43. The air, after passing through this sector, may be slightly diluted with products of combustion but has its temperature considerably raised. It is discharged under pressure from the blower 11 10 into the pipe 41 which leads to the furnace and thereby a regenerative effect is obtained, making use of this heat to increase the temperature of the products of combustion from the furnace for more effective activation with less fuel. 15

It will be appreciated that suitable filters or other air cleaning means may be interposed between the air inlets and the adsorber, the gas inlet and the adsorber and, if necessary, between the furnace and the adsorber to prevent particles 20 of dust, dirt or soot from clogging the pores of the adsorbent material for, in the present case, it is preferred to use an adsorbent material having characteristics substantially like silica gel, or the gel of other activated hydrous oxides. 25

The rotary adsorber unit in practical form comprises a hollow cylindrical rotor containing the adsorbent beds, a hood closing each end thereof and containing entrance and exit ports for the various gases and a supporting frame for holding 30 the parts in relative positions and to provide bearings for the central shaft about which the rotor is revolved by any suitable source of power.

In Figures 3 and 7 are shown the top hood 50, which is circular in form, as supported from the four side frame members 51, preferably angle bars joined into a square and each having a flange overlapping and secured to a peripheral flange of the hood. The bottom hood is identical with the top in every respect and is likewise secured to a bottom frame. The top and bottom frames are connected by vertical corner posts, as seen in Figure 7, which may extend to form feet. It is considered desirable to operate the device with the axis vertical but this is not necessary. 45 A suitable bearing member 52 is carried by a spider 53 from each hood and journaled for rotation in these bearings is the central shaft 54 having thereon a suitable gear or worm wheel within the housing 55 driven by a worm or other 50 gearing from the shaft 56 of the motor 57 suitably supported above the top hood in any convenient manner.

As best seen in Figures 5 and 7, the rotor is provided with spiders 58 which support it from 55 the shaft 54 so that it is rotated therewith.

Figure 5 shows clearly the inner and outer cylindrical shells 16 and 17, concentrically mounted and formed of sheet steel, each of the same length and each reinforced top and bottom 60 by angle bar 60. This bar has one flange secured against the outer side of the shell and the remaining flange 61 radial and positioned even with its end of the cylinder. Each shell is lined with a layer of suitable heat insulating material, for instance, sheet asbestos 63, 64, respectively. 65

The ends of the shells are open and the space included between them has been referred to as the adsorption chamber. As seen in Figures 2 and 4, it is divided into a series of full length sector-like compartments by means of the substantially radial partitions each formed in two parts 70 and 71 and extending from the inner to the outer shell and from the top to the bottom 75

thereof. The compartments thus formed are each traversed at a sharp angle by a thin bed of adsorbent material. Alternate beds 12 are inclined to lean in the direction of rotation of the rotor and the remaining ones in the opposite direction. Each of these beds is of uniform thickness and the adsorbent material thereof is confined between a pair of screens 14 or 15 spaced uniformly apart throughout their areas and each 10 screen extending from the inner to the outer shell and substantially for the full height thereof. The beds are inclined circumferentially to engage one partition at the top and the adjacent partition at the bottom, whereby they extend angularly across the passage through the adsorption chamber between adjacent partitions so that the gas in flowing longitudinally through any compartment must flow through the bed of adsorbent material therein.

20 The adsorber beds on opposite sides of the same partition are oppositely inclined so that their adjacent ends are against the intermediate partition and their opposite ends respectively against adjacent partitions on opposite sides of the intermediate one. This ensures that any 25 gases engaging a partition which is between seals will be of the same temperature, which will be explained in more detail later. The beds may be said to be arranged so that in edge view four of 30 them form a W with inlets and outlets in the three V's one inverted, comprising the W.

For ease in construction the rotor is assembled from the two concentric cylinders or shells with their end reinforcements and a plurality of 35 similar screen units each including a pair of adsorber bed screens, a partition and a number of vertical spacers 16 and 17. These spacers are formed of metal plates substantially triangular in shape and arranged at right angles to the partition plate and parallel to the axis of the rotor. Each extends to the inner face of the screen and is secured thereto by welding or brazing to form 40 a support therefor. But two spacers are shown for each screen, but it will be obvious that any 45 requisite number may be inserted and positioned as desired.

These units comprising the two screens, the partition and associated parts, best seen in Figure 6, are all identical in construction and are arranged alternately in the annular space between the outer and inner cylinders by reversing them 50 top for bottom. Each is triangular in vertical chordal section as seen in Figure 2 and in horizontal section is a trapezoid. When alternated 55 and arranged in the space between the two cylinders at proper intervals there remains between each two of the units a space such as designated 12 or 13 in Figure 2, which is to receive the adsorbent material.

60 In detail these units include the substantially flat partition plate 10 which is slightly shorter than the length of the cylinders but has one of its ends bent over in a direction opposite to the direction of rotation of the rotor to form the arcuate seal engaging tip 80 at the end thereof, which is flush with the shell end.

The outer edge of the partition plate is bent substantially at right angles to the main part as at 81, in Figure 4, and there is welded at 82 a 70 plate 83 bent in the opposite direction to form the oppositely disposed triangular wings at the outer edge of the partition plate. At the inner edge a similar arrangement is provided by the bent over portion 84 and the welded angle plate 75 85. The spacers 16 and 17 are attached as by

welding or riveting to the intermediate portions of the partition plate as seen in Figure 4.

About the skeleton thus formed is wrapped the screen which will form the sides of adjacent adsorber beds. This may be effected by brazing or spot welding one edge of the screen with the inner edge as 85 extending the screen along one face of the unit, across the outer end over wings 81 and 83, along the other face, and finally over 84 to which it is secured. It may be suitably attached at points of contact with the skeleton. The top and bottom of the unit are left open and the free edges of the screen around these openings are reinforced by the metal straps 86 at the spaced edges. Where the screens converge 15 and meet as at 90, with the edge of the partition 70 opposite the curved tip 80, they are secured thereto in any suitable manner as by welding.

The units are distributed in the annulus between the cylinders to provide a uniform spacing 20 between the screens of adjacent ones for the reception of the adsorbent material and are secured in position by radial screws such as 91 on the outer cylinder and 92 on the inner cylinder which pass through openings in the cylinders and are received in openings in the wings 81, 83 and 84, 85, respectively. Conveniently self-tapping screws can be used, of the type used in sheet metal work, which draw the wings tightly down against the 25 insulating sheet on the interior of the shells and provide a gas-tight fit. The wings being somewhat flexible, permit the units to be made slightly less in length than the space between the cylinders to permit convenient assembly, the screws drawing the wings down into engagement with 30 the shells.

In order to close the adsorber beds proper to retain the adsorbent therein, the spaces between adjacent screens at their upper and lower edges are closed by caps. Conveniently a cap 94 extends across the edge of the partition 70 and 40 closes the adjacent ends of two beds. Such a radial cap 94 comprises the flat bottom sheet of uniform width substantially equal to twice the thickness of an adsorber bed. It has the marginal 45 U-shaped flanges 95 which fit over the edges of the outer screens and their reinforcing straps 86. A channel member 96 secured to the center of the inner side of the cap member fits tightly over 50 the junction of the two inner screens and the partition.

End flanges 97 on the caps fit respectively against the inner and outer shells, as clearly seen in Figure 5, and are secured thereto by means of the bolts 98, thus reinforcing the structure and 55 providing a direct connection between the inner and outer shells. In assembly, the bottom caps are all placed in position and the adsorbent material is then filled into the spaces remaining between the units, providing the beds of uniform thickness, after which the top caps are put in position, retaining the adsorbent material permanently in the beds.

Each cap has secured centrally to its outer surface the plate member 71 which extends radially and has a curved end 100 thereon identical with the curved end on the opposite end of the partition plate 70, of which it forms an extension, to form a true division between the two adsorber beds which are oppositely inclined against it at 70 the end on which the cap is placed.

As before stated, the rotor is mounted between end hoods which provide the inlet and outlet passages for the gases and which confine the various gas streams to the requisite number of ad-

sorber beds. To prevent leakage between adjacent streams of gas which are of different constituents or under different conditions of moisture content and the like, and to prevent outward leakage or infiltration, a number of seals are necessary and since they are identical in the top and bottom hoods, which are also otherwise exactly the same, they will be described for but one.

Each hood comprises an annular sheet metal disc 102 having inner and outer diameters respectively less and greater than the corresponding shells of the rotor. It has suitably secured thereto and fitting within the peripheral flanges 103 and 104, the border rings 105 and 106, and spaced 15 a short distance inward from these, the corresponding ring members 107 and 108, leaving the narrow annuli 109 and 110 for the reception of the peripheral seals.

The seals comprise the annular members 111 and 112 formed preferably of compressed woven asbestos, impregnated with graphite for lubrication purposes, conveniently formed of two sheets of the same thickness, and together forming a close sliding fit between the plates 105, 107 or 25 106, 108 adapted to have their lower edges rest on the flanges 61 of the reinforcing angles for the rotor shells to form a gas-tight fit and permit the rotor to rotate in respect to the seals.

The inner and outer seals are the same and the 30 remaining description will be confined to the outer and upper one. Above the seal member 111 is a soft rope 114 of asbestos or similar material impregnated with graphite which is overlaid by a circle of sector-like metal pressure plates 115 35 each having at least a pair of spaced pins 116 extending upwardly therefrom surrounded by the coil springs 117 which bear beneath the adjusting plates 118 whose position is adjustable to vary the tension on the springs by means of the 40 adjusting screws 119 and lock nuts which cooperate with the plate 102. The pressure exerted by the springs on the pressure plates 115 not only serves to cause intimate contact between the lower edges of the seal member 111 and the flange 45 61, but expands the soft rope 114 into close lateral engagement with the plates 105 and 107 to prevent any leakage around the edges of the seal 111. It will be appreciated that the seal is continuous around the whole periphery but that the 50 pressure plates 115 and the spring abutment plates 118 are in sectors for convenience in adjustment of the springs.

Between the respective ports through the hood as seen in Figure 3, there are arranged radial 55 seals which separate the adsorber beds into groups through which the various gases pass, the beds in each group being in multiple in respect to the flow of gases and not in tandem.

Each radial seal, of which there are the same 60 number as there are ports through the hood and which number may vary in accordance with the manner of using the adsorber, is constructed in the same manner and a description of one will be sufficient. This seal must extend from the outer peripheral seal to the inner peripheral seal and must make contact at all times with at least one of the partition plates.

It takes the form of a sector-like metal plate 65 121 having secured thereto the sheet 122 of similar material to the seal 111 and having an arcuate extent somewhat greater than the arcuate distance between adjacent partitions.

The radial seal overlaps the reinforced edges 70 of the shells to the extent of the width of one-half of the inner and outer peripheral seals and

for this purpose the inner half of each peripheral seal is cut away for the arcuate extent of the radial seal, and bears closely at 123 on the upper surface of the metal plate 121. The inner guide for each of the peripheral seals is cut away 5 for the same purpose as seen in Figure 5.

Viewing Figure 2 and considering the upper seal, it will be seen that the plate 121 has secured to its upper surface a pair of spaced radial strips 125, each having secured to each side thereof a sheet 126 of the same type of sealing material as used in the peripheral seals and these composite assemblies 125, 126 fit between the combined guide and partition plates 127 and 128 which divide the hood into compartments and permit 15 vertical movement of the seals. The guide plates 127 are the legs of a U-shaped plate having the base 129 secured to a metal plate 130 which is in turn secured to the portions 131 forming extensions of the guides 128 which are attached as at 20 132, in a gas-tight manner to the top plate 102 of the hood. In this manner the seals are removable for inspection or renewal. Each of the sliding seals for the radial seal is provided with a soft rope 133 to prevent leakage in the manner 25 described in connection with the peripheral seals. This rope is covered by a strip 134 pressed downwardly by coil springs 135, surrounding pins 136, the springs being compressed by a plate 137 adjusted by the bolt 138 and lock nut which cooperate with the plate 130 in the manner seen in Figures 2 and 5.

The spring pressure plates 137 have their ends positioned to cooperate, on movement, with the legs of U-shaped members 140 secured between 35 the guide plates 127 and 128. This prevents pressure plate displacement. Any suitable arrangement for a similar purpose is provided for the pressure plates 118 of the peripheral seals. This arrangement must also prevent rotation of 40 any of the peripheral seal parts due to the friction of the seal with the flange of the rotor.

The spaces between adjacent seals each constitute either the inlet or the outlet to a portion of the adsorber beds, the exact number being determined by the extent of the arc between the 45 seals, which is adjusted for the desired air or gas flow through the adsorber beds. Suitable ports 150 are provided for access to these spaces.

The disposition of the adsorber beds in the annular space between the two cylinders of the rotor is zig zag or sinuous as seen in Figure 2 providing the entrances for the gases in the V's A between beds. From these V's the gases pass through the beds B, B, Figure 2, to the outlet V's 55 C on the opposite side. The partitions are in the centers of the V's and are exposed on both sides to gas of the same temperature and pressure in the intermediate positions in any section between any pair of seals.

The gases passing through the adsorber beds change their temperature in this passage, those giving up moisture to the beds becoming warmer and those taking up moisture from the beds becoming cooler. If the partitions were so disposed 65 that they had on one side entering air or gases and on the other side exit air or gases from the beds, there would be a large heat loss through the metal of the partitions unless expensive insulation were provided. With the present disposition alternate partitions are exposed on both sides respectively to inlet and outlet gases and there is no heat loss through them.

The only exception to this rule is in connection with the partitions which are actually in en- 75

gagement with the radial seals which then form the true partitions between sectors of the adsorber chamber and prevent the intermingling of gases in different phases of the process, but since there are so few partitions under these conditions and then not at all times, the losses here are inconsequential. It will be seen that the radial seals are somewhat greater in arcuate extent than the space between any two adjacent partitions so that one adsorber bed will be completely cut out of use when the partitions on opposite sides thereof engage the same radial seal. In such case there is a dead gas space for a time, between gases in different phases. Losses by heat transfer through partitions occur only when single seals are in an intermediate position such as shown in Figure 2.

The arrangement of the seals is particularly effective, preventing any possibility of leakage radially or circumferentially either into or out of the rotor or between adjacent sections thereof.

These devices can be built in various sizes to accommodate different volumes of air or gas. The same general constructional features may be used for all reasonable size devices. One feature which may be of importance in making the device of larger size is some means to maintain the beds of adsorbent material of substantially uniform thickness throughout their extent so that the flow of gas is not localized therein. This may be effected conveniently by so disposing the spacer plates 76, 77 in the units that instead of being opposite each other on the two sides of an adsorber bed, they are alternately disposed so that if there is any distortion of the screens due to settling or packing of the adsorbent material, the whole bed will take a sinuous form, but will remain of substantially uniform thickness.

This last feature is well shown in Figure 8 where the spacers in the units F are arranged with three on the right of the partitions and two on the left. Those in the reversed unit G are similarly positioned. This disposes three on one side of each adsorber bed H and two on the other with staggered relation. In this arrangement two types of unit are necessary, one for disposition, as F, and the other for reversed positioning, as G.

Having thus described the invention, what is claimed as new and desired to be secured by Letters Patent is:

1. An adsorber unit of the continuous type including, in combination, two concentric shells defining therebetween an adsorption chamber, a plurality of partitions each extending between said shells and from end to end thereof and dividing the chamber into a plurality of individual compartments, an adsorber bed in each compartment extending from shell to shell and from near one end of one partition to near the opposite end of the adjacent partition to be thus interposed between the ends of the compartment said bed being of less thickness than the distance between adjacent partitions.

2. An adsorber unit of the continuous type including, in combination, two concentric shells defining therebetween an adsorption chamber, a plurality of partitions each extending between said shells and from end to end thereof and dividing the chamber into a plurality of individual compartments, an adsorber bed in each compartment extending from shell to shell and from near one end of one partition to near the opposite end of the adjacent partition to be thus interposed between the ends of the compartment, adjacent beds being oppositely inclined in re-

spect to the partitions, said bed being of less thickness than the distance between adjacent partitions.

3. An adsorber unit of the continuous type including, in combination, two spaced coaxial plates in the form of closed figures, a plurality of beds of adsorbent material each extending between said plates, a partition between each pair of beds and dividing the space between said plates into compartments each traversed by an adsorbent bed of less thickness than the distance between adjacent partitions, means to deliver gases through a plurality of beds in multiple, said beds being so positioned in respect to said partitions that substantially the whole of each partition is exposed on both sides to gas at the same conditions.

4. An adsorber unit of the continuous type including, in combination, two spaced, concentric shells of the same length, substantially radial plates dividing the annular space into a plurality of compartments open at the shell ends, an adsorbent bed traversing each compartment, each bed being larger in extent than the transverse area of the compartment and adjacent beds being arranged symmetrically in respect to the interposed partition.

5. An adsorber unit of the continuous type including, in combination, two spaced, concentric shells of the same length, substantially radial plates dividing the annular space into a plurality of compartments open at the shell ends, an adsorbent bed traversing each compartment, each bed being larger in extent than the transverse area of the compartment and means to deliver gases longitudinally through several compartments in multiple.

6. An adsorber unit of the continuous type including, in combination, two spaced, concentric shells of the same length, a pervious layer of adsorbent material extending between said shells, said layer having parts disposed at angles to each other to present entrance and exit V's for gas toward the two ends of the shells.

7. An adsorber unit of the continuous type including, in combination, two spaced, concentric shells of the same length, a pervious layer of adsorbent material extending between said shells, said layer having parts disposed at angles to each other to present entrance and exit V's for gas toward the two ends of the shells and axially disposed partitions extending from end to end of said shells and dividing said layer into sections.

8. An adsorber unit of the continuous type including, in combination, two spaced, concentric shells of the same length, a pervious layer of adsorbent material extending between said shells, said layer having parts disposed at angles to each other to present entrance and exit V's for gas toward the two ends of the shells, axially disposed partitions extending from end to end of said shells and dividing said layer into sections, a hood closing each end of said space between shells, an inlet port in one hood, a similarly positioned outlet port in the other hood and a seal defining each radial side of each port and adapted to cooperate successively with each partition as the shells rotate in respect to the hoods.

9. A rotor for an adsorber of the continuous type comprising inner and outer concentric shells, a plurality of units connecting said shells, each unit comprising a partition plate extending between said shells and a pair of screens secured to said plate and extending between said shells,

adjacent units having adjacent screens cooperating to hold adsorbent material.

10. A rotor for an adsorber of the continuous type comprising inner and outer concentric shells, 5 a plurality of units connecting said shells and each comprising a partition plate extending from shell to shell substantially radially, and two screens each secured to one radial edge of said plate and diverging therefrom and extending between said shells.

11. A rotor for an adsorber of the continuous type comprising inner and outer concentric shells, 10 a plurality of units connecting said shells and each comprising a partition plate extending from shell to shell substantially radially and two screens each secured to one radial edge of said plate and diverging therefrom and extending between said shells, said units being alternately reversed in position whereby adjacent screens 15 are uniformly spaced and adsorbent material between such screens.

12. A rotor for an adsorber of the continuous type comprising inner and outer concentric shells, 20 a plurality of units connecting said shells and each comprising a partition plate extending from shell to shell substantially radially, and two screens each secured to one radial edge of said plate and diverging therefrom and extending between said shells, said units being alternately reversed in position whereby adjacent screens are 25 uniformly spaced, a cap spanning the meeting edges of the screens of each unit and closing the ends of the spaces between these and adjacent screens.

30 13. A unit assembly for a rotary adsorber including, in combination, a substantially flat partition plate adapted to be mounted substantially radially, a triangular flange at the outer edge thereof, a smaller triangular flange at the inner edge thereof, a screen near each face of said plate and stretching from flange to flange and stiffeners of sheet metal extending away from the plate 35 and secured to the screens.

14. A unit assembly for a rotary adsorber including, in combination, a substantially flat partition plate adapted to be mounted substantially radially, a triangular flange at the outer edge thereof, a smaller triangular flange at the inner edge thereof, a screen near each face of said plate and stretching from flange to flange, stiffeners of sheet metal extending away from the plate and secured to the screens, said stiffeners being so spaced from the inner edge of the plate 10 that when alternate units are reversed to bring their facing screens a uniform distance apart the spacer edges will be staggered on opposite sides of the enclosed space between screens.

15. A seal for use between stationary and rotatable parts of a continuous type adsorber including, in combination, a sealing strip adapted to engage one of said parts, the other part having a guide channel for the reception of part of said strip, a pressure plate to press the strip against the first mentioned part, means resiliently urging said plate toward said part and a rope of soft material between said plate and strip and pressed by said plate into engagement with the walls of the channel and the rear of said strip.

16. In a gas adsorber, a housing forming an annular chamber, radial partitions in said chamber forming a plurality of compartments, and a bed of adsorbent material disposed diagonally in each compartment and of less thickness than the distance between adjacent partitions, the two adjacent partitions and bed of adsorbent in cross section forming a letter N.

17. In a gas adsorber, a housing forming an annular chamber, a plurality of beds of adsorbent in said chamber extending from the outer to the inner boundaries of the annulus, any four adjacent beds in cross section forming a letter W and substantially radial central partitions in each of the V's forming the W.
